UNITED STATES PATENT OFFICE.

ALBERT C. COBB, OF HOUSTON, TEXAS.

CENTRIFUGAL BRAKE MECHANISM.

1,263,041.

Specification of Letters Patent.

Patented Apr. 16, 1918.

Application filed March 10, 1914, Serial No. 823,780. Renewed September 11, 1917. Serial No. 190,868.

To all whom it may concern:

Be it known that I, ALBERT C. COBB, citizen of the United States, residing at Houston, in the county of Harris and State of Texas, have invented certain new and useful Improvements in Centrifugal Brake Mechanism, of which the following is a specification.

This invention relates to centrifugal brake mechanism designed primarily for use upon elevators, and has for its object to provide mechanism so arranged upon the elevator car or cage as to be actuatable at a predetermined speed of rotation during normal movement of said car, said mechanism however, being so constructed as to, should the car travel at an abnormal rate of speed, gradually and automatically increase its speed and cause an automatic brake device to be applied and set.

A further object of the invention is to so arrange a plurality of intermeshing gears with respect to a stationary rack as to cause one of said gears, in the event of the loss of the elevator control, to rotate at an exceedingly high rate of speed, whereby to correspondingly rotate a suitable governor having connection with and controlling operation of the above mentioned brake device.

The invention still further aims to provide an exceedingly simple, practical and efficient device wherein the component parts, except the rack aforesaid, are suitably incased and arranged conveniently beneath the floor of the elevator car or cage.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein I have illustrated my improved centrifugal brake.

Referring now to the drawings by numerals, 2 designates as an entirety the elevator shaft, and 4, as an entirety, a two-part casing within which the centrifugal brake mechanism comprising the present invention is arranged. Said casing 4 is adapted for securing in any suitable manner upon the under side of the elevator car (not shown), preferably at one side thereof.

A rail 7, carrying a rack bar 8, is fixedly secured as indicated at 9 to the rear wall of the elevator shaft. The respective longitudinal edges of the rack bar 8 are provided with teeth 10, the teeth upon one side or edge of the said bar being adapted to mesh with a gear 11 mounted upon a suitable shaft 12 journaled within the casing 4 previously referred to. The teeth upon the opposite edge of the rack bar 8 mesh into a like gear 13 mounted upon a second shaft 14 also journaled within the said casing 4. The above arrangement will provide, during movement of the elevator car or cage, for the rotation of the said gears 11 and 13 in opposite directions. Said shaft 12 carries a comparatively large gear 15 while the shaft 14 carries a similar gear 16, the teeth of the said gears 15 and 16 being adapted for meshing engagement as is clearly illustrated in the drawings. A third shaft 17 is journaled within the casing 4, said shaft carrying a pinion 18 meshing into the gear 16 above noted. A comparatively large gear 19 is mounted upon the shaft 17, said last mentioned gear meshing into a pinion 20 mounted upon a fourth shaft 21, the latter being also journaled within the casing 4 aforesaid. Another comparatively large gear 22 is provided, said gear being mounted upon the shaft 21 and positioned for meshing engagement with a pinion 23 mounted upon a fifth shaft 24, likewise journaled within the casing 4. Attached to the pinion 23 and rotatable therewith is a governor device 25, said device comprising in addition to the arms and balls 26 and 27 respectively, a collar 28 the latter being mounted for sliding engagement upon the shaft 24, such sliding movement being controlled by the speed of rotation of the governor device. Arms 29 are pivoted to the sliding collar 28 as indicated at 30, said arms being also pivoted as indicated at 31 to brake shoes 32 in turn pivoted as at 33 to a rod 34 mounted for rotation with the governor 25 and upon the shaft 24. The rod 34 is so positioned with respect to the casing 4 as to rotate within a circular opening 35 thereof, the wall of the opening forming a friction surface against which the shoes 32 of the brake device are forced. Suitable means is provided for locking the rod 34 against sliding movement upon the shaft 24 during a sliding movement of the collar 28.

In operation, should the elevator (not

shown) descend at an abnormal rate of speed, the gears 11 and 13 by reason of their engagement with the teeth 10 of the double rack bar 8 will be rotated at an abnormal rate of speed, said gears correspondingly rotating the comparatively large gears 15 and 16. Rotation of gear 16 imparts a like movement to the pinion 18, which in turn rotates comparatively large gear 19 whereby to in 10 turn rotate pinion 20 into the teeth of which the teeth of the gear 19 mesh. The pinion 20 rotates comparatively large gear 22, and, as the said gear 22 is in mesh with pinion 23, the latter is rotated, by reason of the 15 several pinions and gears, at an exceedingly high rate of speed. As the pinion 23 rotates, the governor device 25 rotates at a corresponding rate, causing it to slide upon shaft 24 and exert outward pressure upon 20 shoes 32. As shoes 32 are forced outwardly or into engagement with the surface 35, it is apparent that the speed of rotation of the gears and pinions aforesaid is checked and, as certain of the said gears mesh with the 25 stationary rack bar 8, a corresponding decrease in the rapidity of descent of the car is effected.

From the above, taken in connection with the accompanying drawings, it will be noted 30 that duplicate gear mechanism is arranged upon each side of the rack bar 8; such arrangement preventing a stripping of the gears in the event of a sudden stopping of the elevator car when descending; that the 35 entire safety appliance, with the exception of the rack bar 8, is movable bodily with the elevator car or cage; and that by the provision of the chain of gears above noted, the governor operating pinion 23 is rotated 40 at an exceedingly high rate of speed upon the rotation of the gears 11 and 13 at a speed in excess of a predetermined rate.

In reduction to practice, I have found 45 that the form of my invention, illustrated in the drawings and referred to in the above

description, as the preferred embodiment, is the most efficient and practical; yet realizing that the conditions concurrent with the adoption of my device will necessarily vary, I desire to emphasize the fact that various 50 minor changes in details of construction, proportion and arrangement of parts may be resorted to, when required, without sacrificing any of the advantages of my invention, as defined in the appended claims. 55

Having thus fully described my invention, what I claim as new and desire to secure by Letters Patent, is:—

1. Centrifugal brake mechanism including an annular brake engaging surface, a shaft having its axis concentric to said surface, a collar loose upon said shaft, a rod mounted on said shaft, a brake shoe pivoted to the rod, and arm connected to the collar and the brake shoe to move said shoe into 65 and out of braking relation with said surface, governor mechanism mounted on the shaft to control movement of said collar, and means to rotate the shaft.

2. Centrifugal brake mechanism including an annular brake engaging surface, a shaft having its axis extending concentric to said surface, a collar loose upon said shaft, a rod mounted on said shaft to terminate adjacent and at diametrically opposite 75 points relatively to said surface, a brake shoe pivoted to each rod terminal, arms connecting the collar and the respective brake shoes to move said shoes into and out of braking relation with said surface, governor 80 mechanism mounted on the shaft to control movement of said collar, and means to rotate the shaft.

In testimony whereof I affix my signature in presence of two witnesses.

ALBERT C. COBB.
